VALUE PRINTING DIE PROTECTION DEVICE

Walter H. Wheeler, Jr., Linden A. Thatcher, and Francis J. Rouan, Stamford, Conn., assignors to Pitney-Bowes Postage Meter Co., Stamford, Conn., a corporation of Delaware

Application September 24, 1942, Serial No. 459,474

7 Claims. (Cl. 101—287)

This invention relates to a die protection device for use in preventing the taking of fraudulent non-metered impressions from the value printing die surface of a printing member in a metered mailing machine.

In the machine disclosed, the printing unit is preferably of the reciprocating type, and it is the principal object of the invention to provide obstruction means whereby the surface of the value printing die will be continuously obstructed both before and during a printing cycle of operation with the exception of the moment of printing.

It is another object to provide obstruction means which is projectable beyond the surface of a printing die during a printing cycle of operation, which is adapted to retract when engaged by a letter upon approaching a printing position, then advance to a projected position after printing, and finally be blocked to prevent the return thereof until the cycle of operation is completed.

It is a further object to maintain control over the projectable obstruction means to prevent the complete retraction thereof during a cycle of operation by any means other than the drive mechanism.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a plan view of a portion of a letter printing machine with such parts shown as directly apply to printing and more particularly to the die protection means;

Fig. 2 is a side elevational view with parts in section and parts broken away, and is taken substantially along the line 2—2 of Fig. 1;

Figs. 3 through 7 are operational views, wherein: Fig. 3 shows the position of the obstruction members during the beginning of a cycle of operation and after the first obstruction means has been removed from an obstruction position; Fig. 4 shows the position of parts at the moment of printing; Fig. 5 shows the position of parts with the platen withdrawn after a printing operation; Fig. 6 shows the blocking of the second obstruc-

tion member in an obstructing position to prevent an attempt to insert a second letter and move it against the printing surface of the printing die; and Fig. 7 shows the comparative positions of both obstruction means when the second obstruction means is being withdrawn from an obstructing position near the end of a cycle of operation.

A printing die block 10 is fixed between side walls 11 and 12 of the printing frame structure and has a value printing die face 13. Directly beneath the die face 13 is a platen 14 which is adapted to be raised to a printing position with relation to the printing die 13 by means of mechanism disclosed in a pending application Serial No. 444,635, filed May 27, 1942. A letter support plate 15, suitably supported by the frame structure has an opening 16 therein through which the platen 14 is adapted to pass during a printing cycle of operation when moving a letter L to a printing position.

An ink roller 17 is rotatably mounted in a support 18 and is normally positioned with the roller in engagement with the forward end of the printing die when the machine is at rest, as best indicated in Fig. 2. The ink roller support 18 is pivotally supported intermediate its ends upon a lever 19, which lever is pivotally mounted upon a shaft 21 carried by the side walls 11 and 12 of the frame structure.

A drive shaft 22, carried by suitable bearings 20—20a in the side walls 11 and 12, is adapted to be rocked by means of a crank 23 when a printing cycle of operation is performed. Fixed to said shaft 22 is a lever 24, which lever has a roller 25 mounted at one end thereof. Through the engagement of said roller 25 with a slot 26 in the lever 19, said lever 19 is adapted to be rocked when any rocking movement of the lever 24 occurs.

When the crank 23 is moved forwardly in the direction of the arrow Fig. 1 to effect a printing stroke, the lever 24 is rocked in a counter-clockwise direction as viewed from Fig. 2, which in turn will effect the rocking of the lever 19 in a clockwise direction and thereby move the ink roller support in a horizontal direction across the face of the printing die 13. The inner ends 18a—18a of the ink roller support are joined with the frame structure by means of link members 26—27, which members are pivotally mounted upon studs 28 and 29 projecting inwardly from the walls 11 and 12 respectively. The opposite ends of said links 26 and 27 are joined with the ink roller support ends 18a—18a by means of a

rod 31. The combined levers 19, 24 and links 26, 27 are arranged to produce a straight line horizontal motion for the ink roller 17 when it is wiped across the printing die 13.

So long as the ink roller 17 and the support 18 are in the path of the printing die 13, the face of the printing die is properly obstructed to prevent the bringing of a letter into engagement with the face of the printing die to obtain a fraudulent impression. After the ink roller 17 is withdrawn from the face of the die to the position shown in Fig. 3, the said die face would normally be exposed if it were not provided with a die protecting means which is adapted to cooperate with the ink roller support 18 to form a second means of obstruction.

The die protecting means comprises a rocker member 33 which is pivoted upon a stud 32 intermediate its ends. At the die obstructing end of the rocker member 33, a hooked plunger portion 34 is provided, the end of which is maintained within an opening 35 in the die block 10 and is urged downwardly through said opening by means of a spring 36. Said spring 36 is fixed to one end of a pin 37, which pin passes through the rocker member 33 and has a head portion 38 projecting beyond the opposite side thereof.

A cam member 39 is fixed to the drive shaft 32, which member has a cam slot 41 therein, a projecting or pointed cam portion 42, and a dwell cam surface 43. Normally the head portion 38 of pin 37 engages the cam slot 41, as shown in Fig. 2, and as the cam is rocked, the head of the pin 38 will first remain stationary, then will be moved by the pointed end 42 to rock the rocker member 33 in a counter-clockwise direction and thereby project the plunger portion 34 beyond the printing die surface, as best shown in Fig. 3. The latter will occur immediately after the end of the ink roller support 18 passes beyond the opening 35 in the die block 10. If, after the head 38 passes the high point of the cam end 42 to a position equivalent to that shown in Fig. 5 for example, an attempt were made to move the plunger end back within the opening 35, the said head 38 would strike the right edge of the pointed cam 42 to thus prevent removal of the plunger from a projecting position. When the head 38 is in a position opposite the dwell 43, the platen will have moved the letter into engagement with the printing die surface. In this manner the plunger portion 34 is always under complete control of the drive.

Pressure is maintained against the letter and printing die through the platen, in the manner described in the afore-mentioned patent application, until the cam member 39 reaches the end of its stroke, which is substantially the position shown in Fig. 4.

The rearward end of the rocker arm 33 has a toe portion 44 bent at right angles to its face, which toe is adapted to cooperate with a latch mechanism generally indicated at 45. Said latch mechanism comprises a substantially horizontally disposed member 46, which is freely pivoted upon the drive shaft 22, and a vertically disposed member 47 which is pivotally mounted upon a stud 48 projecting from the side wall 12. A latch is effected between the two latch members 46 and 47 by the engagement of a notched sidewardly disposed arm 49 with a slotted portion 51 of an inwardly bent wall 52 of the latch member 47. When the device is in its rest position, the latch members are normally in the latched position shown in Fig. 3.

When during a printing cycle of operation, the letter reaches the position of engagement with the printing die surface, the toe portion 44 of the rocker member 33 will have engaged the upper edge of the latch member 46, as indicated in Fig. 4, to rock the notched portion of said latch member 46 out of latched engagement with the wall 52 of the latch member 47. Said latch members 46 and 47 are urged about their pivots in a counter-clockwise direction by means of springs 53 and 54 respectively, the spring 53 being attached to arm 49 of the latch member 46, and spring 54 being attached to a projecting lug 50 forming a part of the latch member 47. Upon engagement therefore, between the toe portion 44 and the upper edge of the latch member 46, the latch will be released and the vertically disposed latch member 47 will be urged against the toe 44, as best shown in Fig. 4.

On the return or restoring stroke of the crank handle 23, the platen 14 will be moved downwardly out of a printing position, and through the spring 36, the arm 33 will be rotated in a counter-clockwise direction to urge the plunger portion 34 beyond the surface of the printing die. Also, the toe portion 44 of the arm 33 will have moved away from the latch member 47 to thus permit said latch member 47 to be urged by spring 54 against the side of the drive shaft bearing 20, as in Fig. 5. In said latter position the upper edge of the latch member 47 is positioned directly beneath the toe 44 to provide a block and thereby prevent complete return movement of the plunger 34 until the cycle of operation is completed, as best indicated in Fig. 6.

Restoration of the latch member to a latching position is effected when a projection 56 on the cam member 39 engages a cam ridge 57 on the latch member 47, in a manner best shown in Fig. 5.

Having described the invention, what is claimed is:

1. In a value printing device having a printing die and platen, means for effecting protection against the taking of impressions fraudulently comprising, inking means normally obstructing the printing die surface, a reciprocating drive means connecting the inking means with the drive to effect removal of the inking means during a printing cycle of operation and return same after printing, a plunger normally withdrawn from the printing die surface in a non-obstructing position, means controlled by the drive to extend the plunger beyond the die surface before the removal of the inking means therefrom, said plunger being removable from an extended position during a printing cycle of operation and being extensible after printing, and means to prevent the return of the plunger to a non-obstructing position until the inking means returns to an obstructing position.

2. In a value printing device having a printing die and platen, means for effecting protection against the taking of impressions fraudulently comprising, a movable inking member normally obstructing the printing die surface, a reciprocating drive, means connecting the inking member with the drive to effect movement of the inking member away from the printing die during a printing cycle of operation and return same to an obstructing position after printing, a plunger normally withdrawn within the printing die and projectable through the printing die surface, means controlled by the drive to extend the plunger beyond the die surface before the inking

member has been entirely removed from said die surface, said plunger remaining partially extended until the moment of effective printing engagement between an article to be printed and the printing die, means to urge the plunger beyond the die surface as the printed article moves away from a printing position, and means to block the return of the plunger to its normally withdrawn position until the inking member is returned to an obstructing position.

3. In a value printing device having a printing die and platen, means for effecting protection against the taking of impressions fraudulently comprising, an inking roller and support therefor normally obstructing the printing die surface, a reciprocating drive, means connecting the inking roller support with the drive to effect movement of the inking roller across the printing die during a printing cycle of operation and return same to an obstructing position after printing, a plunger normally withdrawn within the printing die and projectable through the printing die surface, means controlled by the drive to extend the plunger beyond the die surface before the inking roller has been entirely removed from said die surface, said plunger remaining partially extended until the moment of effective printing engagement between an article to be printed and the printing die, means to urge the plunger beyond the die surface as the printed article moves away from a printing position, and means to block the return of the plunger to its normally withdrawn position until the inking roller is returned to an obstructing position.

4. In a value printing device having a printing die and platen, means for effecting protection against the taking of impressions fraudulently comprising, inking means normally obstructing the printing die surface, drive means connected with the inking means to effect removal thereof during a printing cycle of operation, a plunger projectable through the printing die surface, cam means controlled by the drive to project the plunger beyond the die surface before the complete removal of the inking means therefrom, said plunger being retractable from a projected position during a printing cycle of operation, means controlled by the cam to limit the retractable position of the plunger end with respect to the printing die surface during the printing stroke, said latter means being adapted to also effect projection of the plunger when the printing stroke has been completed, and means to block the complete return of the plunger during the return stroke of the drive means until the inking means returns to an obstructing position.

5. In a value printing device having a printing die and platen, means for effecting protection against the taking of impressions fraudulently comprising, an inking member normally obstructing the printing die surface, a drive connected with the inking member to effect movement thereof away from the printing die during a printing cycle of operation, a plunger member projectable through the printing die surface, means connecting the drive with the plunger to extend the plunger beyond the die surface before the inking member has been removed from said

die surface, means associated with the drive and plunger to prevent independent movement of the plunger toward the printing die surface, means to yieldably urge the plunger to a projecting position after printing, plunger blocking mechanism positioned in a non-blocking relation with the plunger member before printing is effected and being movable to a blocking position after printing is effected, whereby, upon projection of the plunger after printing, the said plunger will be prevented from being returned to a non-obstructing position by any means except the drive.

6. In a value printing device having a printing die and platen, means for effecting protection against the taking of impressions fraudulently comprising, an inking member normally obstructing the printing die surface, a drive connected with the inking member to effect movement thereof away from the printing die during a printing cycle of operation, a plunger member projectable through the printing die surface, cam means connecting the drive with the plunger to extend the plunger beyond the die surface before the inking member has been removed from said die surface, a projection on said cam associated with the plunger member to prevent independent movement of the plunger toward the printing die surface, a spring connected with the plunger to yieldably urge said plunger to a projecting position after printing, plunger blocking mechanism positioned in a non-blocking relation with the plunger member before printing is effected and being movable to a blocking position after printing is effected, whereby, upon projection of the plunger after printing, the said plunger will be prevented from being returned to a non-obstructing position by any means except the drive.

7. In a value printing device having a printing die and platen, means for effecting protection against the taking of impressions fraudulently comprising, an inking member normally obstructing the printing die surface, a drive connected with the inking member to effect movement thereof away from the printing die during a printing cycle of operation, a plunger member projectable through the printing die surface, means connecting the drive with the plunger to extend the plunger beyond the die surface before the inking member has been removed from said die surface, means associated with the drive and plunger to prevent independent movement of the plunger toward the printing die surface, means to yieldably urge the plunger to a projecting position after printing, normally latched blocking mechanism positioned in a latched non-blocking relation with the plunger member before printing is effected, means controlled by the plunger member to trip the latched blocking mechanism, when printing is effected, and means to urge the blocking mechanism to a blocking position, whereby, upon extension of the plunger after printing, the said plunger will be prevented from being returned to a non-obstructing position by any means except the drive.
